BUZZER FOR BICYCLES AND THE LIKE

Hisashi Saitou, Kasugai, Japan, assignor to Kabushiki
Kaisha Saikosha Seisakusho, Kasugai, Aichi, Japan

Filed Aug. 16, 1974, Ser. No. 498,007

Term of patent 14 years

Int. Cl. D10—06

U.S. Cl. D10—116

FIG. 1

FIG. 2

FIG. 3

FIG. 4

FIG. 5

FIG. 6

FIG. 1 is a perspective view of a buzzer for bicycles and the like showing my new design;

FIGS. 2, 3, and 4 are side elevational views thereof;

FIG. 5 is a top plan view thereof;

FIG. 6 is a bottom view thereof.

The clamp is shown in broken lines for illustrative purposes only.

I claim:

The ornamental design for a buzzer for bicycles and the like, as shown and described.
